UNITED STATES PATENT OFFICE.

JAMES L. NIX, OF HOMER CITY, PENNSYLVANIA.

THERMOSTAT.

No. 857,298.

Specification of Letters Patent.

Patented June 18, 1907.

Application filed July 24, 1906. Serial No. 327,585.

To all whom it may concern:

Be it known that I, JAMES L. NIX, a citizen of the United States, and a resident of Homer City, Pennsylvania, have invented certain new and useful Improvements in Thermostats, of which the following is a specification.

My invention relates to improvements in thermostats, and has for its object to provide a simple and economical thermostat especially adapted for use in incubators.

In the drawings: Figure 1 is a perspective view of the thermostat of my invention in place upon the wall of an incubator. Fig. 2 is a perspective view of an incubator showing the connecting means between the thermostat and the heat valve. Fig. 3 is an enlarged longitudinal plan view of the thermostat. Fig. 4 is an enlarged perspective view of the thermostat in place upon the wall of an incubator. Fig. 5 is a transverse sectional view showing the mode of attachment of the thermostat to the wall of the incubator.

The thermostat of my invention comprises a channeled metallic strip 5 seated within a channeled metallic strip 6, the strip 6 having its side walls cut away at a point between its ends as indicated by the numeral 7, and being slightly bent at the point where its walls are so cut away. A third channeled strip-member 8 is mounted upon the strip 6, being cut away at a point between its ends as indicated by the numeral 9; the strips 8 and 6 being attached to each other at the point where their side walls are cut away, by the rivet 10. Within the channeled strip 8 the channeled-member 11 is seated. The strips 5 and 6 are connected at their outer extremities by the rivet 12. The strips 8 and 11 are connected at their outer ends by the rivet 13; and the four strips or channeled-members 5, 6, 8 and 11 are secured rigidly to each other at their ends opposite to those secured by the rivets 12 and 13, by the rivet 14.

Within the channeled-member 11 at a point near the fixed end of the thermostat, I have provided the bracket-member 15, which is riveted to the member 11 by the rivet 16; the inner end of the bracket-member 15 being secured to the wall of the incubator by the screws 17. At the free or operating end of the thermostat the strip-members 8 and 11 are secured to the bracket 18. The bracket 18 is recessed as indicated by the numeral 19 to receive the bell-crank-lever 20,

which is pivotally mounted within the bracket 18 at the point indicated by the numeral 21.

The inner arm 22 of the bell-crank-lever 20 is provided with a connecting bolt 23 whose threaded end extends through the outer end 24 of the strip-member 5, and is provided with the thumb-screw 25. The outer arm 26 of the bell-crank-lever 20 extends through the opening 27 in the wall of the incubator, and at its outer extremity 28 is provided with a screw-threaded connecting rod 29, which connects it to the valve lever 30. The rod 29 is provided at its lower end with the thumb-screw 31 to facilitate the adjustment of the valve lever 30. The valve lever is pivotally mounted in the bracket 31. It is provided at one end with a counter-balancing weight 32, and at the opposite end with the valve 33, which is seated over the flue 34, and is adapted to open or close said flue 34 to control the temperature within the incubator.

Among the advantages of this form of thermostat are the following. The thermostat may be attached to the back, side, bottom, or ceiling of the egg-chamber, and can be worked in a horizontal or vertical position. It is very simple of construction, the thermostat proper embodying but four members. It is very effective in practice, a thermostat of this construction having developed five times the movement and power of the ordinary thermostat used for incubator purposes in the prior art and containing twice the weight of metal employed in the present thermostat. The strips 6 and 8 are composed of the same kind of metal, say zinc, while the strips 5 and 11 are of one kind, say steel, being less expansible.

Having fully described my invention, what I claim as new and desire to have secured to me by the grant of Letters Patent, is:

1. In a device of the class described, two inner channeled-members secured back to back at a point between their ends, and being bent outwardly from said point to their outer extremities; two outer channeled-members set in the first named channeled-members, the four members being secured together at their inner ends, and the outer channeled-members being secured to the inner channeled-members at their outer ends, substantially as described.

2. The herein described thermostat comprising the channeled-members 6 and 8, a channeled-member 5 seated in the channeled-member 6, the channeled-member 11 seated in the channeled-member 8, the members 5, 6, 8 and 11 being rigidly secured together at their inner ends, the members 6 and 8 being secured to each other at a point between their ends, the members 5 and 6 being secured together at their outer ends and the

members 8 and 11 being secured to each other at their outer ends, substantially as described.

In testimony whereof, I have signed my name to this specification, in presence of two subscribing witnesses.

JAMES L. NIX.
